Primary Examiner — Catherine S Posthauer*Assistant Examiner* — Joan E. Diehl(74) Attorney, Agent, or Firm — Manabu Kanesaka(57) CLAIM

The ornamental design for a jar for cosmetics, as shown and described.

DESCRIPTION

FIG. 1 is a perspective view of a jar for cosmetics showing my new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof;

FIG. 8 is a cross-sectional view thereof along the line 8-8 in FIG. 4; and,

FIG. 9 is a perspective view of a jar for cosmetics base, wherein the lid is removed to show aspects not visible when combined.

The broken lines depict portions of the jar for cosmetics that form no part of claimed design.

1 Claim, 3 Drawing Sheets(56)
